TRANSFORMER WITH REGULATABLE
LEAKAGE REACTANCE

Eduard Fries, Zurich-Oerlikon, Switzerland

Application October 6, 1945, Serial No. 620,731

10 Claims. (Cl. 171—777)

1. The invention relates to transformers with variable reactance and while not limited thereto is particularly applicable to welding transformers whose secondary reactance must be varied within wide limits.

My copending application, Serial Number 490,787, filed June 14, 1943, Patent No. 2,411,370 granted November 19, 1946 discloses a transformer having a closed primary magnetic core provided with primary windings and secondary windings telescoped over the former with a transverse space between each primary and the respective secondary core with an adjustable air gap. The construction is such, that the secondary core is inductively interlinked with the secondary coil or coils only. The present application is a continuation in part of the aforementioned application and affords a structure in which a portion of the primary core completes the magnetic path of the secondary magnetic flux and vice versa. This results in substantial savings in material and in a compact structure of relatively small size and high efficiency.

The present invention has for its object to provide a transformer of the aforementioned type which is simple in construction, requires a minimum of active material and is highly efficient in operation.

Another object is to provide in a transformer having primary and secondary windings magnetic cores affording paths for the primary and for the secondary fluxes, so disposed that the reluctance of the primary magnetic circuit is substantially unaffected by the adjustment of the reluctance of the secondary magnetic circuit.

Another object is to provide a unitary structure of a transformer having a variable secondary reactance, including a secondary magnetic circuit which is inductively coupled with the secondary winding only, and the reluctance of which is adjustable without affecting the reluctance of the primary magnetic circuit.

Another object is to provide a high reactance transformer having primary and secondary windings, a primary core inductively interlinked with the primary and the secondary winding and a secondary core having a variable reluctance and interlinked with the secondary winding only.

Another object is to provide a unitary transformer and variable reactor with a primary winding inductively mounted on the main magnetic frame of said transformer and a secondary winding inductively interlinked with said main frame and also with a secondary magnetic frame pro-

vided with a variable air gap, each of said frames having a part which completes the magnetic path for the magnetic flux induced in the other frame.

Other objects and advantages will hereinafter appear.

The accompanying drawings are illustrative of several embodiments of the invention. In the drawings,

Fig. 1 is a vertical section of a single phase transformer embodying the invention.

Fig. 2 is a top view and partially a cross-section along the lines 2—2 of Fig. 1.

Fig. 3 is a side view of a modification of the magnetic frame shown in Figs. 1 and 2.

Fig. 4 is a vertical section of a modified detail of Fig. 3.

Fig. 5 is a section along the lines 5—5 of Fig. 4 and

Fig. 6 is a section along the lines 6—6 of Fig. 4

Referring to the drawing, Figs. 1 and 2, the same illustrates a core type transformer having a pair of primary windings 10 and 11 and a coordinated pair of secondary windings 12 and 13, telescoped over the coils 10 and 11, respectively. The transverse cross section of the coils 10 to 13, inclusive, is substantially rectangular and the transverse space between the coils 10 and 12 and the coils 11 and 13, respectively, is increased on one side to provide for the passage of a secondary magnetic core or frame therethrough, as will appear hereinafter. The coils 10 and 11 are mounted on the vertical legs 14 and 15 respectively, of a primary or main magnetic core or frame 16, the lower end of these legs being connected by a yoke 17. The legs 14 and 15 and the yoke 17 form a substantially U-shaped magnetic core or frame. The upper ends of the two legs 14 and 15 are provided with in-turned polar extensions 18 and 19, respectively. The secondary magnetic circuit comprises an inverted substantially U-shaped magnetic core or frame 20 having the legs 21 and 22, respectively, and a yoke 23. The transverse distance between the coils 10 and 12 and 11 and 13 is such that the legs 21 and 22 of the secondary core can freely slide therebetween. The distance between the polar extensions 18 and 19 is bridged by the yoke 23 of the secondary core. Thus the primary magnetic circuit including the core 17 is substantially closed, except for the narrow gaps 24 and 25 between the polar extensions 18 and 19 and the yoke 23, which gaps are just sufficient to permit a free sliding longitudinal movement of the secondary core within the primary core. The secondary magnetic circuit is completed

through variable air gaps 26 and 27 between the yoke 17 and the legs 21 and 22, respectively. By moving the secondary core up and down within the secondary coils, the length of these air gaps is varied, thus varying the reactance of the secondary magnetic circuit.

It will be noted that the primary windings 10 and 11 which closely embrace the legs 14 and 15, respectively, are only interlinked with the primary magnetic circuit, while the secondary coils 12 and 13 which embrace corresponding legs of both the primary and secondary core are interlinked with both magnetic circuits. Thus by varying the air gaps 26 and 27, the reactance of the secondary circuit may be varied without varying the reactance of the primary circuit. Fas- 16 tened to the yoke 17 and aligned with the legs 21 and 22, respectively, are flat magnetic or non- magnetic guide bars 28, which are straddled by the two halves of the secondary core legs, so that 20 one half of the laminations of said core legs is arranged on each side of said guide bars 28 to slide longitudinally thereon.

The guide bars 28 are provided with lateral extensions 29 adjacent to the polar extensions 18 and 19, which extensions are inserted between the laminations of the polar extension and riveted thereto. The secondary core legs are provided with insulating bolts 30, the ends of which are threaded and provided with nuts 31 and washers 32, interposed between the nut or the bolt heads and the laminations to hold the latter together and to press them against the guide bars to permit movement of the secondary core relative to the primary core, to thereby vary 35 the air gaps 26 and 27 between the respective parts of the secondary magnetic circuit.

To provide for adjustment of the air gap the secondary core yoke 23 has affixed thereto a tapped boss 34 and a similar tapped boss 35 is 40 affixed to the yoke 17 of the primary core. A threaded shaft 36 provided with a hand wheel 37 engages the threads in the bosses 34 and 35. The threads in the bosses 34 and 35 and on the corresponding parts of the shaft 36 are cut in 45 opposite directions, so that upon turning of the shaft 36 by the hand wheel 37, the secondary core is moved toward or away from the yoke 17 of the primary core to thereby vary the air gaps 26 and 27 and thus the reactance of the secondary magnetic circuit.

The apparatus functions in the following manner: When the primary coils 10 and 11 are connected to an alternating current source, a current flows throughout them which produces a 50 magnetic flux in the legs 14 and 15. This flux induces an electromotive force in the secondary coils 12 and 13 in the usual manner, the open circuit secondary voltage. If now the secondary coils are connected to an external circuit, as for instance a pair of welding electrodes, a current flows in the secondary winding. This current generates a leakage magnetic flux which passes through the leakage legs 21 and 22. This 55 leakage magnetic flux is in opposition to the primary magnetic flux in the legs 14 and 15, thus reducing the voltage induced in the secondary coils. The current flowing in the secondary coils 12 and 13 as well the leakage magnetic flux in the legs 21 and 22 will increase to such an extent until the sum of the magnetic fluxes in the legs 14 and 21 respectively 15 and 22 induces a reduced voltage which corresponds to the welding arc-voltage. The longer the air gaps 26 and 27 are adjusted, the greater is the 75

current which flows in the secondary coils 12 and 13 in order to get the required value of leakage magnetic flux in the legs 21 and 22. On the other hand the open circuit secondary voltage of the transformer is not substantially affected by the length of the air gaps 26 and 27. By adjustment of the air gaps it is thus possible to adjust the welding current within very wide limits.

Fig. 3 illustrates a modification of the magnetic frame shown in Figs. 1 and 2. The primary magnetic core 40 is similar to the core 16 of Fig. 1, except that the legs 41 and 42 are not provided with inturned polar extensions. A secondary magnetic frame 43, corresponding to the frame 20 of Fig. 2 has core legs 44 and 45, which extend only partly through the interspaces between the primary and secondary coils. The yoke 46 of the primary core is provided with polar extensions 47 and 48 which are in alignment with the legs 44 and 45, respectively, to form with the latter variable air gaps 49 and 50, respectively, in the secondary magnetic circuit. The yoke 51 of the secondary magnetic frame 43 is provided with lateral extensions 52 and 53 at its ends, to bridge the magnetic gap between the ends of the core legs 41 and 42, the latter being of such length that the reluctance of the air gaps 54 and 55 between the extensions 52 and 53 and the core legs 41 and 42 is not affected by the movement of the secondary frame 43. The air gaps 54 and 55 are only sufficient to afford sliding movement between the respective parts and do not affect materially the reluctance of the primary magnetic circuit.

In the modifications Figs. 4, 5 and 6, a number of the laminations in the center of the core legs 41 and 42, are shortened to provide a slot 56. A corresponding number of laminations of the yoke 51 are extended to form a tongue 57 which fits in the slot 56. The legs 41 and 42 are each further provided with an elongated hole 58 to afford free movement of a threaded bolt 59 which passes also through an elongated hole 60 in the tongue 57 of yoke 51 to afford free movement of the latter. The bolt is provided with nuts 61 at its ends and spring washers 62 are interposed between the nuts and the leg, to provide for resilient engagement therebetween so as to compress the laminations and prevent vibration, while permitting relative movement between the primary and secondary core.

Other modifications within the scope of the present invention and appended claims will be obvious to those skilled in the art.

What I claim as new and desire to secure by Letters Patent is:

1. A transformer providing for substantial variation of its secondary reactance in response to variations of its secondary current, comprising, a first pair of legs and a first yoke to form therewith a unitary substantially U-shaped primary magnetic core, a second pair of legs and a second yoke to form therewith a unitary substantially U-shaped secondary magnetic core, coplanar with an inverted relative to said primary core, said second yoke being located and arranged to provide a magnetic bridge between the open ends of said primary core, said first yoke providing a magnetic bridge including a pair of air gaps between the open ends of said secondary core, a pair of primary windings each encircling one each of said first pair of legs and

a pair of secondary windings, each secondary winding encircling one each of said first pair of legs and the corresponding one of said second pair of legs and having its inner circumferential wall spaced from the outer circumferential wall of the respective primary winding to afford passage therethrough of the respective leg of said secondary pair of legs.

2. A transformer providing for substantial variation of its secondary reactance in response to variations of its secondary current, comprising, a first pair of legs and a first yoke to form therewith a unitary substantially U-shaped primary magnetic core, a second pair of legs and a second yoke to form therewith a unitary substantially U-shaped secondary magnetic core coplanar with and inverted relative to said primary core, an intermediate portion of said secondary core being located and arranged to provide a magnetic bridge between the open ends of said primary core, an intermediate portion of said primary core providing a magnetic bridge including a pair of air gaps between the open ends of said secondary core, a pair of primary windings each encircling one each of said first pair of legs and a pair of secondary windings, each secondary winding encircling one each of said first pair of legs and the corresponding one of said second pair of legs and having its inner circumferential wall spaced from the outer circumferential wall of the respective primary winding to afford passage therethrough of the respective leg of said secondary pair of legs.

3. A transformer providing for substantial variation of its secondary reactance in response to a variation of its secondary current, comprising, a first pair of legs and a first yoke to form therewith a unitary substantially U-shaped primary magnetic core, a second pair of core legs and a second yoke to form therewith a unitary substantially U-shaped secondary magnetic core inverted relative to and coplanar with and reciprocable within said primary core, said second yoke being located and arranged between the open ends of said primary core to provide with the latter a magnetic circuit of substantially constant reluctance for all relative positions of said cores, the intermediate portion of said first yoke providing a magnetic bridge including a pair of variable air gaps between the open ends of said secondary core, a pair of primary windings each encircling one of said first pair of legs, and a pair of secondary windings, each secondary winding encircling one of said first pair and the corresponding leg of said second pair of legs and having its inner circumferential wall spaced from the outer circumferential wall of the respective primary winding to afford passage therethrough of the respective leg of said secondary pair of legs.

4. A transformer providing for substantial variation of its secondary reactance in response to a variation of its secondary current, comprising, a first pair of legs and a first yoke to form therewith a unitary substantially U-shaped primary magnetic core, a second pair of core legs and a second yoke to form therewith a unitary substantially U-shaped secondary magnetic core inverted relative to and coplanar with and reciprocable within said primary core, said second yoke being located and arranged between the open ends of said primary core to provide with the latter a magnetic circuit of substantially constant reluctance for all relative positions of said cores, the intermediate portion of said first yoke providing a magnetic bridge including a pair of variable air

gaps between the open ends of said secondary core, a pair of primary windings each encircling one each of said first pair of legs, and a pair of secondary windings, each secondary winding encircling one each of said first pair of legs and the corresponding one of said second pair of legs and having its inner circumferential wall spaced from the outer circumferential wall of the respective primary winding to afford passage therethrough of the respective leg of said secondary pair of legs.

5. A transformer providing for adjustment of its secondary reactance, comprising, a substantially U-shaped primary magnetic core having its poles provided with inturned extensions, a coplanar substantially U-shaped secondary core reciprocable inside of and inverted relative to said primary core to provide a magnetic bridge of substantially constant reluctance between the polar extensions of said primary core for all relative positions of said core and a variable air gap between the end of each of the poles of said secondary core and the opposed intermediate portion of said primary core, a pair of primary windings each encircling one of the legs of said primary core, and a pair of secondary windings, each secondary winding encircling one each of the legs of said primary and the corresponding leg of said secondary core and having its inner circumferential wall spaced from the outer circumferential wall of the respective primary winding to afford passage therethrough of the corresponding leg of said secondary magnetic core.

6. A transformer providing for substantial variation of its secondary reactance in response to a variation of its secondary current, comprising, a first pair of legs, each having at one end thereof a lateral polar extension and a first yoke connecting the other ends of said legs to form therewith a unitary substantially U-shaped primary magnetic core with said polar extensions extending towards the center of said U, a second pair of core legs and a second yoke to form therewith a unitary substantially U-shaped secondary magnetic core inverted relative to and coplanar with and reciprocable relative to said primary core, said second yoke being located and arranged to substantially close the magnetic gap between said polar extensions, said first yoke providing a magnetic bridge including a pair of variable air gaps between the open ends of said secondary core, a pair of primary windings each encircling one each of said first pair of legs, a pair of secondary windings, each secondary winding encircling one each of said first pair of legs and the corresponding leg of said second pair of legs and having its inner circumferential wall spaced from the outer circumferential wall of the respective primary winding to afford passage therethrough of the respective leg of said secondary pair of legs and means to reciprocate said cores relative to each other.

7. A transformer providing for substantial variation of its secondary reactance in response to a variation of its secondary current, comprising, a primary laminated substantially U-shaped magnetic core having a first pair of legs and a first yoke, a secondary laminated substantially U-shaped magnetic core coplanar with and inverted and reciprocable relative to said primary core and having a second pair of core legs and a second yoke, said second yoke being located and arranged between the open ends of said primary core to provide with the latter a magnetic circuit of substantially constant reluctance for all relative positions of said cores,

the intermediate portion of said first yoke providing a magnetic bridge including a pair of variable air gaps between the open ends of said secondary core, a pair of primary windings each encircling one of said first pair of legs and a pair of secondary windings, each secondary winding encircling one of said first pair and the corresponding leg of said second pair of legs and having its inner circumferential wall spaced from the outer circumferential wall of the respective primary winding to afford passage therethrough of the respective leg of said secondary pair of legs, said windings being mounted in fixed relation to said primary core, and means to reciprocate said cores relative to each other.

8. A transformer providing for substantial variation of its secondary reactance in response to a variation of its secondary current, comprising, a stationary primary laminated and substantially U-shaped laminated magnetic core having a first pair of legs and a first yoke, a secondary laminated substantially U-shaped magnetic core coplanar with and inverted and reciprocable relative to said primary core and having a second pair of core legs and a second yoke, said second yoke being located and arranged to provide a magnetic bridge between the open ends of said primary core, said first yoke providing a magnetic bridge including a pair of variable air gaps between the open ends of said secondary core, a pair of stationary primary windings each encircling one of said first pair of legs and a pair of stationary secondary windings, each secondary winding encircling one of said first pair and the corresponding leg of said second pair of legs and having its inner circumferential wall spaced from the outer circumferential wall of the respective primary winding to afford passage therethrough of the respective leg of said secondary pair of legs and means to reciprocate said secondary core.

9. A transformer providing for substantial variations of its secondary reactance in response to a variation of its secondary current, comprising, a first pair of legs, an individual polar extension adjacent to one end of each of said legs and a first yoke connecting the other ends of said legs to form therewith a unitary substantially U-shaped primary magnetic core, a second pair of core legs and a second yoke to form therewith a unitary substantially U-shaped secondary magnetic core inverted relative to and coplanar with and reciprocable relative to said primary core, said second yoke being and said polar extensions being aligned to substantially close the magnetic circuit of said primary magnetic core, an intermediate portion of said primary core providing a

5 magnetic bridge including a pair of variable air gaps between the open ends of said secondary core, a pair of primary windings each encircling one each of said first pair of legs, a pair of secondary windings, each secondary winding encircling one each of said first pair of legs and the corresponding one of said second pair of legs and having its inner circumferential wall spaced from the outer circumferential walls of the respective primary winding to afford passage therethrough of the respective leg of said secondary pair of legs and means to reciprocate said cores relative to each other.

10. A transformer providing for substantial variations of its secondary reactance in response to a variation of its secondary current, comprising, a first pair of legs, an individual polar extension adjacent to one end of said legs and a first yoke connecting the other ends of said legs to form therewith a unitary substantially U-shaped primary magnetic core, a second pair of core legs and a second yoke to form therewith a unitary substantially U-shaped secondary magnetic core inverted relative to and coplanar with and reciprocable relative to said primary core, said second yoke being provided at each end with a polar extension to substantially close the magnetic circuit between the respective free end of each of said primary cores and said second yoke, a polar extension for each of said second pair of legs attached to said first yoke and aligned with the respective leg to provide with said first yoke a magnetic bridge including a pair of variable air gaps between the free ends of said secondary core, a pair of primary windings each encircling one each of said first pair of legs, a pair of secondary windings, each secondary winding encircling one each of said first pair of legs and the corresponding one of said second pair of legs and having its inner circumferential wall spaced from the outer circumferential walls of the respective primary winding to afford passage therethrough of the respective leg of said secondary pair of legs and means to reciprocate said cores relative to each other.
